UNITED STATES PATENT OFFICE.

NATHANIEL SANDERSON, OF NORTH YAKIMA, WASHINGTON.

DESIGN FOR A MATCH-SAFE.

45,404.

Specification for Design.

Patented Mar. 10, 1914.

Application filed January 6, 1914. Serial No. 810,683. Term of patent 7 years.

To all whom it may concern:

Be it known that I, NATHANIEL SANDERSON, a citizen of the United States, residing at North Yakima, in the county of Yakima and State of Washington, have invented a new, original, and ornamental Design for Match-Safes, of which the following is a specification, reference being had to the accompanying drawing, forming a part thereof.

The figure is a perspective view of a match safe showing my new design.

I claim:—

The ornamental design for a match safe as shown.

In testimony whereof, I have signed my name to this specification in the presence of two subscribing witnesses.

NATHANIEL SANDERSON.
